LOCK

Filed April 9, 1931

UNITED STATES PATENT OFFICE

EDWARD N. JACOBI, OF MILWAUKEE, WISCONSIN, ASSIGNOR TO BRIGGS & STRATTON CORPORATION, OF MILWAUKEE, WISCONSIN, A CORPORATION OF WISCONSIN

LOCK

Application filed April 9, 1931. Serial No. 528,824.

This invention relates to certain new and useful improvements in locks and refers more particularly to locks of the general type illustrated in my copending application 5 Serial No. 528,823 and in which the lock cylinder is removably mounted in the mounting head.

In locks having removable cylinders it has been difficult to protect the exposed end 10 portion of the cylinder against destruction and it is, therefore, an object of this invention to provide a lock of the character described which is equipped with adequate means for resisting destruction of its cylinder.

Another object of this invention resides in the provision of a protecting member for the exposed end of the lock cylinder which also serves as part of the means for removably securing the lock cylinder in its mounting head.

Another object of this invention resides in the provision of a novel bolt structure which normally retains an element engaged 25 over the outer end of the lock cylinder against removal from the mounting head and which, upon movement of the lock cylinder beyond one of its normal limits of movement by means of a special key releases 30 said member and consequently the lock cylinder for removal.

And a more specific object of this invention resides in the provision of a protecting cap formed of hardened metal and engaged over the exposed end of the lock cylinder and having a portion extending rearwardly for engagement by the locking bolt of the lock structure whereby the protecting cap is normally maintained assembled with 40 the mounting head and is removable therefrom to permit withdrawal of the lock cylinder upon movement of the locking bolt beyond one of its normal limits of movement.

With the above and other objects in view which will appear as the description proceeds, my invention resides in the novel construction, combination and arrangement 45 of parts substantially as hereinafter described and more particularly defined by the

appended claims, it being understood that such changes in the precise embodiment of the herein disclosed invention may be made as come within the scope of the claims.

In the accompanying drawing, I have 55 illustrated one complete example of the physical embodiment of my invention constructed according to the best mode I have so far devised for the practical application of the principles thereof, and in which: 60

Figure 1 is a view partially in side elevation and partially in longitudinal section of a lock structure embodying my invention;

Figure 2 is a transverse sectional view taken through Figure 1 on the plane of the 65 line 2-2;

Figure 3 is a transverse sectional view taken through Figure 1 on the plane of the line 3-3;

Figure 4 is a view similar to Figure 3, but 70 illustrating the locking bolt in its fully retracted position permitting removal of the lock cylinder;

Figure 5 is a top plan view of the mounting head and lock cylinder removed from 75 the supporting casing, said view being taken on the plane of the line 5-5 of Figure 1 with portions thereof broken away and in section to illustrate structural details; and

Figures 6 and 7 are side elevations of a 80 regular and special key, respectively.

Referring now more particularly to the accompanying drawing in which like numerals designate like parts throughout the several views, the numeral 10 represents the mounting head of a lock structure embodying this invention, which is longitudinally bored, as at 11 to receive a lock cylinder 12 inserted therein from one end. The lock cylinder 12 is of more or less conventional construction and is equipped with a plurality of locking tumblers which are yieldably urged to project one end into one of a pair of diametrically opposite longitudinal tumbler receiving grooves 14 formed in the 85 mounting head in communication with its bore 11.

The tumblers 13 are retractile within the lock cylinder by the insertion of a proper key 15 into the key slot 16 of the lock cyl- 100

inder to free the lock cylinder for rotation. Rotation of the lock cylinder is adapted to impart longitudinal motion to a locking bolt 17 at the inner end of the lock cylinder, the lock cylinder being provided with an eccentric cam 18 projected from its inner end for the purpose of transmitting motion to the locking bolt, as will be later described.

The locking bolt is slidably mounted in 10 a transverse groove or slot 19 formed in the inner end portion of the mounting head and is yieldably urged, by means of an expansive spring 20 confined between a medial portion of the locking bolt and a cup 15 member 21 detachably disposed in an opening 22 in the wall of the mounting head in line with the locking bolt, to project its outer end portion 23 beyond the surface of the mounting head. The projected end 23 20 of the locking bolt passes through an opening 24 in a rearward extension 25 on a protecting cap 26 engaged over the outer end of the mounting head and adapted to removably secure the lock cylinder in the mounting head in a manner to be later described, 25 and projects beyond the surface of the rearward extension 25, which is flush with and forms a continuation of the cylindrical outer surface of the mounting head, to extend into an opening 27 formed in a supporting casing or tube 28. With the locking bolt thus 30 projected into the opening 27, the movement of the mounting head and lock cylinder within the supporting casing is prevented, and upon withdrawal of the locking bolt 35 out of the opening 27, the mounting head and lock cylinder, which comprises the lock structure per se, is free to be bodily moved axially within the supporting casing or tube 40 28.

Longitudinal or axial movement of the lock structure may be effected in any manner to produce any desired action and in the present instance an expansive spring 29 45 mounted within the supporting casing 28 inwardly of the lock structure at all times yieldably urges the lock structure outwardly of the casing so that upon disengagement of the locking bolt from the supporting casing opening 27 outward movement of the lock structure takes place. This outward movement, which is brought about by the action of the spring 29, may be transmitted to any desired mechanism (not shown) by 50 means of a wire 30 or the like, and is limited by the extension of the spring cup 21 into an elongated opening or slot 31 in the supporting casing.

The lock cylinder is retained against longitudinal movement in the mounting head to 55 maintain its eccentric cam in proper relation to the locking bolt, in an inward direction by the engagement of an enlarged head or annular flange 35 on the front end of the cylinder with a shoulder 36 formed by coun-

terboring the outer end of the mounting head bore 11, as at 37. Outward movement of the lock cylinder is prevented by the protecting gap 26 which is engaged over its outer end portion and over the adjacent outer end portion of the mounting head, the protecting cap being removably secured on the mounting head by the extension of the locking bolt end 23 through the opening 24 in the rearward extensions 25 of the protecting cap.

The protecting cap may be stamped from a single blank of hardened metal or its outer end may be closed by a separate disc 33 annularly flanged to engage behind an annular flange 32 on the cylindrical portion of the cap. The disc 33 covers the outer end of the lock cylinder and to permit the insertion of a key into the lock cylinder, the disc is provided with an opening 34 in 85 register with the key slot 16.

As hereinbefore stated, the rearward extension 25 of the protecting cap lies flush with the outer cylindrical surface of the adjacent portion of the mounting head and in like manner the entire protecting cap is of the same diameter as that of the mounting head so that upon retraction of the locking bolt by actuation of the lock cylinder, the lock structure is freely movable in the 95 supporting casing.

The locking bolt 17, as best illustrated in Figures 3 and 4, has an enlarged medial portion 38 having one side edge arcuate to conform to the cylindrical shape of the lock cylinder and engage the surface of the bore 11. At its opposite side, the medial portion 38 has an offset extension 39 which lies in the path of the eccentric cam 18 and at its bottom it is bifurcated to provide a pair 100 of spaced arms 40 and 41. The arm 40 forms part of the offset extension 39 and the arm 41 provides a shoulder 42 at its juncture with the arcuate side edge which is normally engaged with a shoulder 43 formed at the 110 juncture of the slot 19 with the bore 11.

It is noted that the outer side edge of the arm 41 diverges from the adjacent side of the slot 19 in a downward direction so that rotation of the lock cylinder causes the locking bolt to rock about the longitudinal axis of the cylinder until the said outer side edge of the arm 41 engages the adjacent side of the slot after which continued rotation of the lock cylinder imparts longitudinal motion to the locking bolt. The rocking action of the bolt effects the disengagement of a lateral lug 44 on the locking bolt outer end portion 23 from a position over one edge of the opening 24 in the protecting cap extension 25.

The engagement of the lateral lug 44 over the edge of the opening 24 precludes the possibility of the bolt being operated by means of a sharp implement inserted into 130

the key slot while the cylinder is in locked position and thus necessitates the use of a proper key to retract the locking bolt out of a supporting casing opening 27 to free 5 the lock cylinder for longitudinal movement.

During normal operation of the lock, the rotation of the lock cylinder is limited to a degree sufficient to draw the locking bolt 10 only out of the supporting casing opening 27, but not out of the opening 24 in the protecting cap extension 25; and this limit of rotational movement on the part of the lock is brought about by means of a key controlled locking lug 45. The locking lug is carried by a spring member 46 fixed to the enlarged head 35 of the lock cylinder and cooperates with an abutment 47 formed on the mounting head in communication with 15 its counterbore 37. The spring member 46, as clearly shown in Figure 2, is mounted in a slot 48 extending partially around the enlarged head 35 with one end firmly anchored therein and its other end, which carries the 20 lug 45, free to move longitudinally with respect to the axis of the lock cylinder.

The resiliency of the spring member 46 normally maintains the locking lug 45 out of the path of the abutment 47, but the regular key 15 is provided with a shoulder 49 (see Figure 6) which engages the free end 30 of the spring member and moves the locking bolt into the path of the abutment 47 so that rotation of the lock cylinder to withdraw 25 the locking bolt from operative position is limited.

When it is desired to remove the lock cylinder, a special key 50, shown in Figure 7, in which the shoulder 49 is omitted, is employed. This key retracts the tumblers as 40 does the key 15, but does not project the locking lug 45 into the path of the abutment 47 so that rotation of the lock cylinder beyond its normal limit is permitted and such additional rotation carries the locking bolt to 45 its fully retracted position illustrated in Figure 4 permitting withdrawal of the protecting cap and consequently the lock cylinder.

50 From the foregoing description taken in connection with the accompanying drawing, it will be readily apparent to those skilled in the art to which an invention of 55 the character described appertains, that I provide a lock structure in which the lock cylinder is removably secured in position by a protecting element secured over the exposed end portions of the mounting head 60 and the lock cylinder and in which a locking bolt normally secures the lock structure in its locked position and also holds the protecting cap assembled with the mounting head to removably secure the lock cylinder 65 in position.

What I claim as my invention is:

1. In a lock structure, including a mounting head and a lock cylinder mounted therein, a protecting element engaged over the exposed end portions of the lock cylinder 70 and mounting head to removably secure the lock cylinder in the mounting head, and means operable by actuation of the lock cylinder for normally holding the protecting element assembled with the mounting head, 75 said last mentioned means being movable to a position releasing the protecting element for detachment from the mounting head upon movement of the lock cylinder beyond one of its normal limits of movement. 80

2. In a lock structure including a mounting head and a lock cylinder having tumblers, the lock cylinder being movable in the mounting head upon retraction of the tumblers, means for removably securing the lock cylinder in the mounting head comprising a protecting element engaged over the exposed portion of the lock cylinder, and a locking bolt operable by the lock cylinder 85 and engaged with said protecting element to hold the same in position. 90

3. In a lock structure of the character described, comprising a mounting head and a lock cylinder removably mounted therein, a protecting element engaged over the exposed 95 end of the lock cylinder to retain the same in the mounting head, a locking bolt operable upon actuation of the lock cylinder, and a releasable connection between the locking bolt and said protecting element. 100

4. In a lock structure including a mounting head and a key operable lock cylinder mounted therein, an element engaged over a portion of the lock cylinder and the mounting head for removably securing the lock cylinder in the mounting head, a locking bolt operable upon actuation of the lock cylinder, and an operative connection between the locking bolt and said element to normally secure said element assembled with the 105 mounting head. 110

5. In a lock structure including a mounting head, a key operable lock cylinder mounted therein, a locking bolt having a predetermined movement during normal actuation of the lock cylinder, means whereby the locking bolt removably secures the lock cylinder in the mounting head, said means being disabled by movement of the lock cylinder to a predetermined position, and key 115 operated means normally preventing movement of the lock cylinder to said position. 120

6. In a lock structure including a mounting head and a key operable lock cylinder mounted therein, a locking bolt operable 125 upon actuation of the lock cylinder, and means normally engaged by the locking bolt for removably securing the lock cylinder in the mounting head, said locking bolt being disengageable from said means to en- 130

able withdrawal of the lock cylinder upon movement of the locking bolt beyond one of its normal limits of movement.

7. In a lock structure including a mounting head and a lock cylinder having key operable tumblers, the lock cylinder being movable in the mounting head upon retraction of the tumblers, a protecting element engaged over the exposed portion of the lock cylinder and the adjacent portion of the mounting head, and means for detachably retaining the protecting element assembled with the mounting head comprising, a locking bolt operable upon actuation of the lock cylinder, and a connection between the locking bolt and said protecting element.

8. In a lock structure including a mounting head and a key operable lock cylinder mounted therein, a member engaged with the mounting head and the lock cylinder for removably securing the lock cylinder in the mounting head, a locking bolt operable upon actuation of the lock cylinder, means whereby the locking bolt normally holds said member assembled with the mounting head, said locking bolt being movable to a position enabling detachment of said member from the mounting head upon movement of the lock cylinder to a predetermined position, and key operable means normally preventing movement of the lock cylinder to said predetermined position.

9. In a lock structure including a mounting head and a key operable lock cylinder mounted therein, a member engaged over the exposed portion of the lock cylinder and adjacent portion of the mounting head to resist destruction thereof, means for detachably maintaining said member assembled with the mounting head to maintain the lock cylinder in the mounting head comprising a locking bolt operable upon actuation of the lock cylinder and normally projected through an opening in said member, said locking bolt being retractible out of the member opening to enable withdrawal of said member to permit removal of the lock cylinder upon movement of the lock cylinder beyond one of its normal limits of movement, and key operable means normally preventing movement of the lock cylinder beyond said normal limit of movement.

10. In a lock structure including a mounting head and a key operable lock cylinder mounted therein, a protecting cap engaged over the outer end of the lock cylinder and mounting head to removably secure the lock cylinder in the mounting head, said protecting cap having an aperture, and a locking bolt operable upon actuation of the lock cylinder and normally projected into said

aperture to hold the protecting cap on the mounting head.

11. In a lock structure including a mounting head and a key operable lock cylinder mounted therein, a protecting cap engaged over the outer end of the lock cylinder and mounting head to removably secure the lock cylinder in the mounting head, said protecting cap having an aperture, a locking bolt operable upon actuation of the lock cylinder and normally projected into said aperture to hold the protecting cap on the mounting head, said locking bolt being retractible from said aperture to release the protecting cap for removal upon movement of the lock cylinder to a predetermined position, and means normally preventing movement of the lock cylinder to said predetermined position and requiring the use of a special key to effect movement of the lock cylinder to said predetermined position.

12. In a lock structure including a mounting head and a key operable lock cylinder mounted therein, a member engaged over a portion of the lock cylinder and mounting head to removably secure the lock cylinder in the mounting head, a locking bolt operable upon actuation of the lock cylinder and normally operatively connected with said member to retain the same assembled with the mounting head, detachment of said locking bolt from said member being effected by movement of the lock cylinder beyond one of its normal limits of movement, and means whereby a special key is required to produce such additional movement of the lock cylinder.

13. In a lock device of the character described, including a mounting head having a key operable lock cylinder movable therein, a supporting element adapted to receive the mounting head, a locking bolt operable upon actuation of the lock cylinder and normally holding the mounting head against movement in the supporting element, a protecting cap engaged over the exposed portion of the lock cylinder and mounting head and having an apertured portion through which the locking bolt passes whereby said protecting cap is held assembled with the mounting head to removably secure the lock cylinder in position, said locking bolt being disengaged from the supporting element upon a predetermined movement of the lock cylinder and being retracted out of the aperture in the protecting element upon an additional movement thereof, and means whereby a special key is required to effect such additional movement of the locking bolt.

14. In a lock structure of the character described, including a mounting head and a key operable lock cylinder having a key slot mounted within the mounting head, a locking bolt carried by the mounting head

- at the inner end of the lock cylinder, said locking bolt having a portion normally projected through an opening in the mounting head to an operative position, a lateral lug
5 on said portion of the locking bolt to overlie one edge of said opening whereby a rocking movement of the locking bolt is required before it can be retracted into said opening, and means whereby the normal
10 operation of the locking bolt by means of the lock cylinder first imparts a rocking movement to the locking bolt and then a longitudinal motion to retract the same within said opening.
- 15 15. In a lock structure including a mounting head and a key operable lock cylinder therein, a locking bolt having a portion normally projected through an opening in the mounting head and retracted upon actuation of the lock cylinder within said opening, means for preventing retraction of the locking bolt until the locking bolt is rocked out of its normal position about an axis at substantially right angles to its direction
20 of retraction, and means whereby the normal operation of the lock cylinder effects such rocking movement of the locking bolt.
16. In a lock structure including a mounting head and a key operable lock cylinder rotatable therein, a locking bolt having a portion normally projected through an opening in the mounting head and retractable within the mounting head upon actuation of the lock cylinder, means whereby
30 rocking movement of the locking bolt about the axis of rotation of the lock cylinder is necessary before the locking bolt can be retracted, and means operable by the normal operation of the locking bolt for effecting
35 said rocking movement on the part of the locking bolt.
17. In a lock structure including a mounting head, a lock cylinder having key operable tumblers and movable in the mounting
40 head upon retraction of the tumblers, a locking bolt having a predetermined movement during normal actuation of the lock cylinder, a cooperative connection between the locking bolt and the lock cylinder for re-
45 movably securing the lock cylinder in the mounting head, said connection being releasable by movement of the lock cylinder to a predetermined position beyond its normal range of movement, and key operable
50 means normally preventing movement of the lock cylinder to said position.
- 55 In testimony whereof I have hereunto affixed my signature.

EDWARD N. JACOBI.
